[57] CLAIM

The ornamental design for a fume hood, as shown and described.

DESCRIPTION

FIG. 1 is a perspective view of a fume hood showing my new design, with two of the panels in the raised position and a stand shown in broken line for illustrative purposes only;

FIG. 2 is a front elevational view thereof with a panel in the lowered position;

FIG. 3 is a rear elevational view thereof with the panels lowered;

FIG. 4 is a plan view thereof;

FIG. 5 is a bottom view thereof;

FIG. 6 is a side elevational view thereof taken from the left of FIG. 2, with the panel lowered; and

FIG. 7 is a side elevational view thereof taken from the right of FIG. 2, with the panel lowered.
